UNITED STATES PATENT OFFICE.

FERDINAND PELZ, OF GLIESMARODE, BRUNSWICK, GERMANY.

AUTOMATIC WEIGHING-SCALE.

No. 831,093.

Specification of Letters Patent.

Patented Sept. 18, 1906.

Application filed May 9, 1905. Serial No. 259,541.

To all whom it may concern:

Be it known that I, FERDINAND PELZ, a citizen of Germany, residing at Gliesmarode, Brunswick, Germany, have invented 5 new and useful Improvements in Automatic Weighing-Scales, of which the following is a specification.

This invention relates to a weighing-scale which is so constructed that the bucket first 10 receives the main bulk of the charge to be weighed and then a supplemental charge. After the bucket has thus been filled to accurately counterbalance the weight it is automatically dumped, returned to its initial 15 position, and recharged.

The scale is delicate in its operation, works quickly, and insures correct results.

In the accompanying drawings, Figure 1 is a side elevation, partly in section, of a scale 20 embodying my invention; Fig. 2, a vertical transverse section, partly in elevation, thereof with some of the parts omitted or broken away. Figs. 3, 4, and 5 are details of the hopper and gates, showing the latter in consecutive positions; and Fig. 6, a detail of the 25 automatic stopping mechanism.

The letter A indicates the frame of the scale, to which is fulcrumed at a' the scale-beam a. The beam is provided at each end 30 with a pair of oppositely-extending arms a² a³. From the arms a² is suspended by hangers b' the beam-board b, carrying the weights b². From the arms a³ are suspended a pair of hangers c d, to which is fulcrumed at 35 e' the overbalanced unsymmetric bucket or receiver e, and which are guided by arms c' d'.

Vertically above receiver e there is a hopper f, having two differently-sized discharge-nozzles f' f². Admission of the material to 40 be weighed to the larger nozzle f' is partly obstructed by a partition f⁴ intermediate the nozzles and by an inclined deflector f³, arranged above nozzle f' and directed toward nozzle f². By this construction the nozzle 45 f² must be covered up to the upper edge of partition f⁴ before any material is admitted to nozzle f'. Consequently there always remains in the hopper above nozzle f² a deposit of material sufficient for the supplemental filling of the bucket and without regard to the inflow of material into the hopper.

The outflow from the larger nozzle f' is controlled by a supply-gate g, having arms 50 g', that turn on arbors h. An opening g² of the gate becomes alined with the smaller

nozzle f² in the closed position of the gate. The outflow from the nozzle f² is controlled by an imperforate supply-gate i, fulcrumed to arbor h by arms i'. Stops g³ i² on the 60 arms g' and i', respectively, engage an abutment A' and limit the downward movement of the gates. The diffusion of the material to be weighed is prevented by brushes f⁵ g⁵, secured to the parts f and g, respectively. 65

To maintain the gate g in its open position, there is fulcrumed to arbor h a locking-lever j, against which rests a stud g⁴ of gate g. The lever j is locked in an inclined position when the bucket is raised by means of a pin 70 e' on the bucket, which engages the lower free end of the lever j, Fig. 1.

The gate i is maintained in its open position by a roller i³, journaled in one of the arms i'. This roller rests upon an offset k' of 75 a latch k, fulcrumed at k² and overbalanced at k³. The latch k is locked in position by one arm of a lever or detent l, which is fulcrumed at l'. The other arm of this detent is located vertically above a knife-edge extension b³ of one of the hangers b' of beam-board b.

The lever i', carrying the roller i³, is extended beyond arbor h, as at i⁴, and to this extension is pivoted at m' a catch m, guided 85 by a pin m² and a slot m³. The lower curved end of catch m is adapted to engage a hook c², pivoted at c³ within a slot of hanger c and engaged by a pin or stop e³ of bucket e.

In order to cause the gates g and i to successively close prior to the counterbalancing of the weights b² by the charged bucket e, the following construction has been devised: To frame A is fulcrumed at n' a lever n, one arm of which is adapted to be engaged by a hook b⁴ of hanger b'. The second longer arm of lever n is adapted to be engaged by a roller o', journaled between the upper bifurcated arm of a bell-crank o, fulcrumed to frame A at o². The lower arm of bell-crank 100 o carries a counterweight o³, which tends to press roller o' against lever n. A nose o⁴ on weight o³, adapted to engage a stop o⁵, limits the descent of the weighted bell-crank o. A weight p, slidable upon a rail p', mounted on 105 lever n, permits the scale to be accurately adjusted to different materials flowing at different speed.

In order to prevent the bucket from emptying should it receive an excessive charge by 110 reason of some defective operation of the scale, the construction shown in Fig. 6 has

been devised. The hanger d of bucket e has a bifurcated upper end d^2 , adapted for the reception of a weight q . This weight has a slot q' and a cross-arm q^2 resting loosely upon fork d^2 . The slot q' embraces a pin r' on one arm of a three-arm lever r , the second arm of which carries a weight r^2 , while its third arm has a hook r^3 , which is adapted to engage a pin or stop i^3 of arm i' .

10 The operation is as follows: When the bucket e is empty and elevated, both gates g and i are raised, so that the larger nozzle f' is open and the nozzle f^2 is closed by gate g , Fig. 3. The material to be weighed should be so charged into hopper f that the latter is permanently filled to a certain level. The material will thus flow through nozzle f' into bucket e . During this operation the counterweight o^3 , in conjunction with lever n , 15 partly counterbalances, and thereby diminishes, weights b^2 . When a quantity of the material to be weighed has thus been received by bucket e , which corresponds to the diminished weights b^2 , the bucket e will descend, 20 together with left arm of lever n . The descent of the bucket will withdraw stop e^2 from locking-lever j , which thus liberates nose g^4 of gate g . The latter now swings down to close nozzle f' and open nozzle f^2 , 25 Fig. 4. The descent of left arm of lever n , causes a corresponding descent of weight o^3 until the nose o^4 contacts with the stop o^5 , and thereby relieves lever n from the burden of the weight. Thus while the material 30 flows through the nozzle f^2 the weights b^2 are only counteracted by the excess of weight of the left arm of lever n over its right arm. When the bucket has been filled to balance the reduced weights b^2 , the extension b^3 of 35 hanger b' will in ascending tilt detent l to release latch k and liberate roller i^3 . The gate i will thus drop to close nozzle f^2 and stop the flow of the material from the hopper, 40 Fig. 5. The object of the slight premature closing of gate i is to allow for the small 45 quantity of material dropped from the hopper while the gate is being closed. The closing of gate i will swing extension i^4 upward to raise catch m into engagement with hook c^2 and cause the latter to liberate pin e^3 . The bucket being thus unlocked will now tilt 50 on fulcrum e' and discharge its contents into a chute s , after which the bucket will automatically right itself and be raised by weights b^2 into its initial position. While the bucket 55 is thus righted the stop e^2 will throw back lever j , and the latter will, by engaging stud g^4 , open gate g . The stud g^4 by engaging a corresponding nose i^6 of gate i will simul-

taneously open the latter. Should for some 60 reason an excessive charge be received by bucket e , the latter will descend beyond its normal position and will thereby permit the descent of weight q . The latter will tilt lever r and cause its hook r^3 to engage stop i^5 , 65 and thereby lock gate i . This prevents the catch m from releasing bucket e , so that the latter will not be dumped.

A suitable registering device is preferably connected with the scale.

What I claim is—

1. A scale provided with a hopper, a pair of nozzles communicating therewith, a partition between the nozzles, a deflector above the first nozzle and directed toward the second nozzle, and a pair of gates for successively closing the nozzles, substantially as specified.

2. A scale provided with a beam, a bucket suspended from one end thereof, a hanger suspended from the other end of the beam, a hook on said hanger, a lever adapted to be engaged by the hook, a counterweight adapted to be brought into or out of engagement with the lever, a detent adapted to be engaged by the hanger, a catch controlled by the detent, and a supply-gate operatively connected with the catch, substantially as specified.

3. A scale provided with a pair of discharge-nozzles, a pivoted perforated gate for closing the first nozzle, a pivoted imperforate gate for closing the second nozzle, a beam, an overbalanced bucket suspended from one end thereof, a hanger suspended from the other end of the beam, a hook on said beam, a lever engaged by the hook, a counterweight adapted to engage the lever, means for closing the perforated gate upon the descent of the bucket, means for disengaging the counterweight from the lever, a detent adapted to be engaged by the hanger, and a latch controlled by the detent and operatively connected to the imperforate gate, substantially as specified.

4. A scale provided with a beam, a hanger suspended therefrom, a bucket pivoted to the hanger, a weight supported upon the hanger, a three-arm lever adapted to be engaged by the weight, and a discharge-gate adapted to be engaged by the lever, substantially as specified.

Signed by me at Brunswick, Germany, this 22d day of April, 1905.

FERDINAND PELZ.
